HAIR DYER AND BLEACHER

Abraham Ostroff, Philadelphia, Pa.

Application February 14, 1940, Serial No. 318,961

12 Claims. (Cl. 132—9)

This invention relates to a device for treatment of the hair and more particularly for a device by means of which the hair may be either dyed or bleached.

5 An object of this invention is to provide an improved means in the form of a perforated liquid dispersing means and a receptacle connected to the dispersing means with a manually operable valve for controlling the amount of liquid 5 discharging from the receptacle into the dispersing means.

Another object of this invention is to provide an improved means for discharging a liquid into the hair, the discharging means including a liquid 15 distributing means which is adapted to prevent the liquid from flowing onto the scalp.

A further object of this invention is to provide a liquid discharging nozzle and a fountain or receptacle connected to or communicating with 20 the nozzle together with an improved means controlling the flow of the liquid from the receptacle or reservoir to the nozzle.

A still further object of this invention is to provide an improved reservoir or fountain for a 25 liquid treating liquid which is so constructed that a predetermined quantity of liquid may be placed in the receptacle for discharge through the distributing or dispersing nozzle into the hair.

A further object of this invention is to provide in combination with a perforated nozzle or liquid discharging means, a removable liquid distributing member which is engageable about the nozzle and which is adapted to be saturated by 30 the liquid discharging from the nozzle.

35 Embodying the objects aforesaid and others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within scope of the invention as 40 claimed.

45 In the drawing:

Figure 1 is a vertical section of a hair treating means constructed according to an embodiment of this invention.

50 Figure 2 is a bottom plan view of the device.

Figure 3 is a detailed side elevation of the reservoir or fountain in an inverted or liquid receiving position.

55 Figure 4 is a sectional view taken on the line 4—4 of Figure 1.

Figure 5 is a fragmentary sectional view taken on the line 5—5 of Figure 1.

Referring to the drawing, the numeral 10 designates generally a nozzle which is of tubular construction and which is closed at the opposite ends thereof. The nozzle 10 is provided with a pair of rows of openings 13 in the lower side thereof through which a hair treating liquid is adapted to pass.

The nozzle 10 is of longitudinally arcuate configuration and is provided at substantially its central point with a tube 11 which communicates at one end with the upper or convex side of the nozzle 10. A cap 12 including a bottom wall 14 and a threaded flange 15 is carried by the upper 10 end of the tube 11 and provides a means whereby the nozzle 10 may be detachably connected to a liquid reservoir as will be hereinafter described. The tube or neck 11 is provided with a partition 16 extending lengthwise thereof which is adapted to divide the stream of liquid passing through the neck or tube 11 into two streams.

A reservoir generally designated as 17 is adapted to be removably engaged with the cap 12 and comprises a cylindrical body 18 which at one end 25 is open and is provided with exterior threads 19 extending inwardly from the open end. The cap 12 is adapted to threadably engage the threads 19. The cylindrical body 18 is provided with an annular bead 20 which is adapted to be 30 engaged by the inner end of the cap 12. Preferably a gasket or sealing member 21 is carried by the cap 12 and is adapted to engage the adjacent end of the cylindrical member 18.

The cylindrical body 18 is preferably of transparent construction and is provided at its other end with a closure in the form of a wall 22 which may be formed integrally with the cylindrical body 18 or which may be formed as an annular plate which is provided with a crimped marginal portion 23 engaging a bead 24 carried by the said other end of the body 18. The wall 22 is provided with a plurality of outwardly inclined legs or supporting members 25 which are adapted to support the reservoir 17 when this reservoir is 40 inverted for filling purposes as shown in Figure 3.

The wall 22 at substantially the central point thereof, is provided with one or more air openings 26 and a spring pressed valve member 27 engages the inner side of the wall 22 and is adapted to normally engage over the openings 26 so as to close these openings. The valve 27 is provided with a valve stem 28 and a knob or head 29 which is positioned exteriorly of the wall 22. A 55

spring 30 is disposed about the stem 28 and at one end engages against the wall 22 and at the other end engages against the knob or head 29 so as to normally hold the valve 27 in a closed position. The reservoir 18 is provided on the exterior thereof with a plurality of graduations 31 having indicia 32 associated therewith. The indicia 32 are arranged in progression from the wall 22 so that when the reservoir 18 is inverted as shown in Figure 3, the indicia 32 and the graduations 31 will correctly indicate the quantity of liquid placed in this reservoir.

In order to provide a means whereby the passage of the liquid through the openings 13 may be more equally distributed along the length of the nozzle 10 on its concave side and in order to at least partially retard the flow of the liquid, I have provided a liquid distributing member 33 in the form of a fabric which is adapted to be wound about the nozzle 10 so as to cover the openings 13. The fabric 33 may be held on the nozzle 10 in any suitable manner and in the present instance, the fabric 33 is removably held on the nozzle 10 by means of a U-shaped resilient clamping clip 34. In the use and the operation of this device, the reservoir 18 is initially disconnected from the cap 12 and is inverted as shown in Figure 3. The desired amount and character of fluid is then poured into the reservoir 17 whereupon the cap 12 is threaded onto the threads 19 of the reservoir body 18. At this time the liquid distributing member 33 is wrapped about the nozzle 10 and clamped thereon by the clips or clamping members 34. The entire structure may then be inverted to the position shown in Figure 1 so that the liquid in the reservoir 17 may flow through the neck 11 into the nozzle 10. Due to the fact that the upper end of the reservoir 17 is normally closed the liquid in the reservoir will not readily flow into the nozzle 10. When the nozzle 10 is passed through the hair, the valve 27 is pushed inwardly by means of the knob 29 thus admitting air into the upper end of the reservoir 17 and permitting the liquid to gravitantly flow downwardly into the nozzle 10. As the liquid flows through the openings 13, the liquid will saturate the fabric distributing member 33 and at the same time will prevent the free flowing of the liquid from the nozzle 10 onto the scalp of the patient. By using a liquid distributing member 33, the liquid flowing through the openings 13 will be more evenly distributed along the entire length of the nozzle 10 than is the case where the nozzle 10 is used without a fabric distributing member. Furthermore, by using a fabric distributing member 33, this member may be readily replaced for each head which is being treated, thereby providing a sanitary hair treating device which need not be sterilized in its entirety as the distributing member 33 may be removed after it has been used once, and a clean or new distributing member substituted therefor.

What I claim is:

1. A device for treatment of the hair comprising a perforated liquid dispersing nozzle, a liquid receptacle having an air intake, means removably connecting said receptacle to said nozzle, a spring-controlled valve carried by said receptacle for controlling said intake, a liquid distributor consisting of a web of fabric encompassing said nozzle, and means removably clamping said distributor on said nozzle.

2. A device for treatment of the hair comprising a liquid dispersing nozzle, a liquid reservoir

open at one end, means detachably coupling said reservoir on said nozzle for establishing communication between the open end of the reservoir and said nozzle, a liquid distributor consisting of a web fabric encompassing said nozzle, and means removably holding said distributor on said nozzle.

3. A device for treatment of the hair comprising a liquid nozzle of longitudinally arcuate configuration and provided with openings in its concave side, a combined connecting and liquid conducting tube fixed at one end to said nozzle and rising from the convex side thereof for supplying liquid to said nozzle, a threaded cap fixed to and opening in the opposite end of said tube, a liquid reservoir threaded onto said cap and having an end communicating with said tube, said reservoir formed with an air intake, and a spring controlled valve carried by said reservoir for controlling said intake.

4. A device for treatment of the hair comprising a liquid nozzle of longitudinally arcuate configuration and provided with openings in its concave side, a combined connecting and fluid conducting tube fixed at one end to said nozzle and rising from the convex side thereof for supplying fluid to the nozzle, a threaded cap fixed to and opening in the opposite end of said tube, a liquid reservoir threaded onto said cap and having an open end communicating with the said opposite end of said tube, said reservoir formed with an air intake, a spring controlled valve for controlling said intake, and a plurality of feet carried by said reservoir about said valve.

5. A device for treatment of the hair comprising a liquid nozzle of longitudinally arcuate configuration and provided with openings in its concave side, a combined connecting and fluid conducting tube fixed at one end to said nozzle and rising from the convex side thereof for supplying fluid to the nozzle, a threaded cap fixed to and opening in the opposite end of said tube, a liquid reservoir threaded onto said cap and having an open end communicating with the said opposite end of said tube, said reservoir formed with an air intake, a spring controlled valve for controlling said intake, and a liquid distributing member encompassing said nozzle.

6. A device for treatment of the hair comprising a liquid nozzle of longitudinally arcuate configuration and provided with openings in its concave side, a combined connecting and fluid conducting tube fixed at one end to said nozzle and rising from the convex side thereof for supplying fluid to the nozzle, a threaded cap fixed to and opening in the opposite end of said tube, a liquid reservoir threaded onto said cap and having an open end communicating with the said opposite end of said tube, said reservoir formed with an air intake, a spring controlled valve for controlling said intake, a liquid distributing member encompassing said nozzle, and means detachably holding said distributing member in encompassing relation with respect to said nozzle.

7. A device for treatment of the hair comprising a liquid nozzle of longitudinally arcuate configuration and provided with openings in its concave side, a combined connecting and fluid conducting tube fixed at one end to said nozzle and rising from the convex side thereof for supplying fluid to the nozzle, a threaded cap fixed to and opening in the opposite end of said tube, a liquid reservoir threaded onto said cap and having an open end communicating with the said opposite end of said tube, said reservoir formed with an air intake, a spring controlled valve for controlling said intake, and means detachably holding said distributing member in encompassing relation with respect to said nozzle.

an air intake, a spring controlled valve for controlling said intake, a fabric distributing member wrapped about said nozzle, and resilient clamping means holding said distributing member about said nozzle.

8. In a hair dyer and bleacher, a transparent cylinder provided with quantity indicating means, a closure member for one end of said cylinder provided with an air intake and a normally seated spring controlled valve for controlling said intake, a closure element for the other end of and detachably secured to said cylinder, said cylinder, member and element coacting to form a liquid reservoir, said element having an axially arranged opening, a nozzle consisting of a horizontally disposed hollow body closed at each end, formed with an opening intermediate the ends of its top aligned with said other opening and a series of perforations in its bottom, and a combined connecting and fluid conducting tube aligned with said openings and integral with said element and nozzle.

9. In a hair dyer and bleacher, a transparent cylinder provided with quantity indicating means, a closure member for one end of said cylinder provided with an air intake and a normally seated spring controlled valve for controlling said intake, a closure element for the other end of and detachably secured to said cylinder, said cylinder, member and element coacting to form a liquid reservoir, said element having an axially arranged opening, a nozzle consisting of a horizontally disposed hollow body closed at each end, formed with an opening intermediate the ends of its top aligned with said other opening and a series of perforations in its bottom, a combined connecting and fluid conducting tube aligned with said openings and integral with said element and nozzle, and a partition within said tube disposed lengthwise of the latter.

10. In a hair dyer and bleacher, a transparent cylinder provided with quantity indicating means, a closure member for one end of said cylinder provided with an air intake and a normally seated spring controlled valve for controlling said intake, a closure element for the other end of and detachably secured to said cylinder, said cylinder, member and element coacting to form a liquid reservoir, said element having an axially arranged opening, a nozzle consisting of a horizontally disposed hollow body closed at

each end, formed with an opening intermediate the ends of its top aligned with said other opening and a series of perforations in its bottom, a combined connecting and fluid conducting tube aligned with said openings and integral with said element and nozzle, said nozzle being of materially greater length than the diameter and length of said cylinder, and the vertical cross section of the nozzle being of less diameter than the diameter of the cylinder.

11. In a hair dyer and bleacher, a transparent cylinder provided with quantity indicating means, a closure member for one end of said cylinder provided with an air intake and a normally seated spring controlled valve for controlling said intake, a closure element for the other end of and detachably secured to said cylinder, said cylinder, member and element coacting to form a liquid reservoir, said element having an axially arranged opening, a nozzle consisting of a horizontally disposed hollow body closed at each end, formed with an opening intermediate the ends of its top aligned with said other opening and a series of perforations in its bottom, a combined connecting and fluid conducting tube aligned with said openings and integral with said element and nozzle, and a distributor formed of a web of fabric encompassing said nozzle from end to end thereof.

12. In a hair dyer and bleacher, a transparent cylinder provided with quantity indicating means, a closure member for one end of said cylinder provided with an air intake and a normally seated spring controlled valve for controlling said intake, a closure element for the other end of and detachably secured to said cylinder, said cylinder, member and element coacting to form a liquid reservoir, said element having an axially arranged opening, a nozzle consisting of a horizontally disposed hollow body closed at each end, formed with an opening intermediate the ends of its top aligned with said other opening and a series of perforations in its bottom, a combined connecting and fluid conducting tube aligned with said openings and integral with said element and nozzle, a distributor formed of a web of fabric encompassing said nozzle from end to end thereof, and means for detachably connecting said distributor to said nozzle.

ABRAHAM OSTROFF.
